CRUSHER

Edward T. Peterson, Reading, Pa., assignor to
 Birdsboro Steel Foundry and Machine Company,
 Birdsboro, Pa., a corporation of Pennsylvania

Application August 26, 1932, Serial No. 630,490

18 Claims. (Cl. 83—53)

My invention relates to crusher equipment, for crushing stones and the like into pieces of smaller sizes. Important features of the invention relate more particularly to a double-acting crusher in which an angularly reciprocating rocker presents on its opposite sides crushing jaws that respectively cooperate with normally stationary anvil plates facing the opposite sides of the rocker, each of the jaws on opposite sides of the 5 rocker alternately crushing and retracting as the other respectively retracts and crushes. Other features of the invention relate to anvil plates comprising the normally stationary jaws of crushers. Still other features relate to desirable 10 details of replacement members of crushers.

The features of my invention are generally applicable somewhat less desirably to a single-acting crusher.

A purpose of the invention is to provide equipment of the character indicated adapted to easy and inexpensive manufacture and well suited to the needs of service.

A further purpose is to locate a rotating eccentric that longitudinally reciprocates a link to angularly reciprocate the main rocker of a preferably double-acting crusher, wholly outside of a space directly beneath the rocker in order to make the bearings of the drive shaft more accessible and keep them away from the deleterious action of dust and particles of broken stone or the like incident to the operation of the crusher.

A further purpose is to operate the rocker of a preferably double-acting crusher of the character indicated by a link, making toward its one end under the rocker a heavy duty socket or knuckle joint connection with the rocker, and at its other end longitudinally reciprocated by an eccentric connection with a rotating power shaft outside the space beneath the rocker. I locate 30 the power shaft outside the space beneath the rocker, use a long link and provide a socket or knuckle connection between the link and rocker near the outer end of the link and preferably directly under the rocker axis when the rocker 35 is in mid position.

A further purpose is to deliver the crushed material from one side of a double-acting crusher of the character indicated through an opening in an intermediate portion of a link reciprocating the rocker of the crusher from an eccentric outside of the space beneath the rocker.

A further purpose is to maintain contact between the different parts of socket bearings between the rocker of a crusher and a link, angularly reciprocating the rocker in cooperating re-

lationship, by a resilient tie between an upper portion of the rocker and the link at a part thereof adjacent the bearing.

A further purpose is to protect a shoe and socket bearing beneath the rocker of a preferably double-acting stone crusher, and between the rocker and an outer end of an operating link, from dust and broken particles of stone or the like incident to the operation of the crusher.

A further purpose is to provide a single or double-acting crusher with a crusher jaw that will be unyielding during normal crushing operations and adapted to yield momentarily if subjected to an undesirably high force incident to the presence of an uncrushable body between the 10 rocker and the jaw of the crusher.

A further purpose is to support an anvil (one of the crusher jaws) of a crusher of the character indicated from yielding rearwardly during normal crushing operations by toggle mechanism, 20 adapted to resiliently release if the operating face of the anvil is subjected to abnormal undesirably high pressure due to any uncrushable body between the anvil and the cooperating jaw of the crusher.

A further purpose is to use a knee and socket connection between an upper and rearward end of an anvil and stationary structure above the anvil to prevent an upward yielding of the anvil during crushing.

A further purpose is to maintain the opposing members of a knee and socket connection between an upper and rearward end of an anvil and stationary supporting structure above the anvil normally resiliently pressed together.

A further purpose is to support the upper and rearward end of an anvil rearwardly of the center of gravity of the anvil to maintain the anvil in automatic engagement with toggle supporting mechanism rearwardly of the anvil.

Further purposes will appear in the specification and in the claims.

I have elected to illustrate one only of the many different forms of my invention, selecting a form however that is practical and efficient in operation and which well illustrates the principles involved.

Figure 1 is a broken side elevation of a crusher that embodies a preferred form of my invention.

Figure 2 is a top plan of Figure 1, but with a charging hopper shown in fragment in Figure 1 omitted in Figure 2.

Figures 3 and 4 are vertical sections taken upon the lines 3—3 and 4—4 respectively of Figure 2 in the directions of the arrows.

Figures 5 and 6 are sections of Figure 1 taken upon the lines 5—5 and 6—6 thereof in the directions of the arrows.

Figure 7 is an enlarged detail section taken 5 upon the line 7—7 of Figure 2.

Figure 8 is an enlarged fragment of Figure 3.

Like numerals refer to like parts.

Describing in illustration and not in limitation and referring to the drawings:—

10 In the illustrated embodiment of the invention a supporting shell and frame structure 10, carries pivotally at 11 a main rocker 12 which presents its preferably downwardly diverging opposite faces 13 and 14 to cooperate as the movable crushing jaws with normally stationary anvil members 15 and 16 respectively.

15 Stone or the like is crushed between each anvil 15 or 16 and the adjacent face 13 or 14 of the rocker, the crushing stroke toward one anvil 20 being the retracting stroke from the other and vice versa. The main rocker 12 is thus double acting in its crushing operations, each rocking movement in one direction crushing on one side and retracting on the other and being succeeded 25 by a rocking movement in the other direction that retracts on the first side and crushes on the second.

30 The rocker 12 is extended downwardly from the lower edges of the crushing faces 13 and 14 as a shell 17 that converges to a transverse knee or head 18.

35 The head or knee 18, suitably integral with the shell 17, is axially parallel with the pivotal axis of the rocker and presents along its length arcuate pivot surfaces to shoes 19 and 20 that connect the head with the outer end of a link 21, the shoes and intermediate head fitting between opposite sides of a downwardly tapering opening 22 in the outer end of the link.

40 The link or eccentric rod 21 is longitudinally reciprocated by an eccentric 23 upon a main drive shaft 24 which is supported in vertically divided pillow block bearings 25 carried by the stationary frame structure. The drive shaft 24 45 also supports a pulley 24' and a fly wheel 24''.

45 The main rocker 12 is preferably so formed that when in mid position it is symmetrical with respect to a vertical plane including its pivotal axis, and in this event, the central axes of the drive 50 shaft 24 and of the head 18 are preferably at substantially the same elevation, the drive shaft being laterally offset from the head far enough for the shaft and the eccentric 23 to be wholly out from beneath the crushing jaws of the machine.

55 The outer end of the link 21 is spring pulled upwardly to its wedge shoe and knuckle connection with the head 18 of the main rocker, the strong upward pull upon the outer end of the link bearing upon the shoes and maintaining the shoes in close engagement with the head.

60 This pull is suitably effected by the tie bolts 26 and 27 which make eye and pin connections at 28 with opposite sides of the link 21 adjacent 65 the ends of the head 18 of the rocker, extend upwardly through perforations in side lugs 29 from the rocker and are strongly pressed upwardly by springs 30.

65 The springs 30 surround the tie bolts and are 70 adjustably compressed between the upper sides of the lugs 29 and washers 31 held to place adjustably by lock nuts 32 on the upper ends of the bolts.

75 The shoes 19 and 20 fit arcuately against the head 18 along substantially the length thereof

and externally fit against the taper sides of the opening 22 in the link 21, so that the upward pull of the tie bolts 26 and 27 upon the outer end of the link 21 is supported by the wedge connection between the shoes and the downwardly tapering surfaces of the link on opposite sides of the opening 22.

80 Broken stone or the like, delivering at opposite sides 13 and 14 of the main rocker is guided away from the shoe and head connection between the 10 rocker and link by downwardly sloping transverse walls and baffles 33, 33', 34, 34' and 35 for ultimate delivery out a discharge opening 36 in the bottom of the frame and shell structure.

85 The main rocker is angularly reciprocated by 15 rotation of the drive shaft 24 which is low down and offset from under the crusher to be well out of the way of the discharging broken stone from the crusher.

90 The link 21 is suitably of cast metal and of 20 open web structure with an overall transverse width as best seen in Figure 4 about the same as the overall width of the main rocker 12.

95 The link 21 is provided with a vertical passage 37 through which the broken material from the 25 side of the crusher toward the drive shaft falls to find outlet from the discharge opening 36 in the bottom of the shell. The baffle walls 34, 34' and 35 guide the delivery from the right side of the main rocker to pass downward into the opening 37 through the link.

100 The wedge shaped opening 22 containing the shoes 19 and 20 and the head 18 of the rocker intermediate the shoes is preferably closed at top and bottom to avoid entry of dust or the like 36 from the discharging product.

105 As illustrated the bottom is closed by a metal plate 38 suitably welded to place while the top is closed by a flexible connection 39.

110 The connection 39 may be of leather or fabric 40 of "bellows" or "accordion" section, fastened around its top at 40 to the downward extension 17 from the main rocker somewhat above the head 18, and held around its bottom by a plate 41 to the link 21 around the top of the taper 45 opening 22, the plate 41 being suitably perforated to pass the head 18.

115 The main rocker 12 includes a hollow casting 42 of form clearly indicated in the drawings, replaceable wear plates 13 and 14 that form the 50 downwardly sloping and relatively diverging side portions of the rocker, and a cover 43 removably mounted along the top of the casting 42 above the pivotal axis thereof.

120 The main casting 42 includes the trunnion extensions 11 that are received and pivoted in cap sleeves 44, the bearing sleeves 44 being mounted in suitable horizontally divided pillow block housings at 45 in the opposite ends of the frame structure.

125 The inner faces of the wear plates 13 and 14 rest upon the correspondingly downwardly sloping and relatively diverging side portions of the main casting 42. Some features of the invention are directed to the means for supporting these 65 wear plates whereby the plates may be readily removed and replaced by new plates and are effectively retained in their operating positions during normal operation of the crusher.

130 The seats of the wear plates 13 and 14 include 70 narrow shelf or lug projections at 46 which receive and hold the bottom edges of the wear plates.

135 The projections 46 make a somewhat acute angle with the adjacent sloping sides of the cast- 75

ing so that when the wear plates fitting against the sloping faces of the casting are pressed diagonally downwardly on to the shelf or lug members 46, they are locked from moving outwardly at the bottom by a suitable angular overlap of the shelf or lug members.

The wear plates and also the anvil members preferably diverge downwardly in their widths, as clearly shown in Figures 5 and 6, Figure 5 showing the crushing face of one of the anvils and Figure 6 showing the crushing face of the cooperating wear plate on the main rocker.

The opposing end walls 47 and 48 of the body of the shell and frame structure 10 are on the inside parallel and vertical. I provide filler members 49 and 50 that are removably mounted on the vertical end walls 47 and 48 respectively to properly case the ends of the anvil plates 15 and 16 and the ends of the downwardly diverging wear plates 13 and 14 of the rocker.

The bottom edges of the filler members 49 and 50 seat upon inward projections 51 from the end walls of the shell and are removably bolted against the shell ends at 52.

The tops of the wear plates 13 and 14 of the main rocker are supported and are strongly pressed downward by the opposite ends of transverse bars 53. These bars are resiliently pressed downwardly by springs 54 which are compressed between the cover 43 of the main rocker and the tops of vertically slid able rods 55 resting upon the transverse bars 53 intermediate the tops of the wear plates.

The downward pressure upon the tops of the wear plates locks the bottoms of the wear plates against the lug projections 46 of the main rocker.

The tops of the wear plates 13 and 14 present groove seats 56 to the opposite ends of the transverse bars 51, see Figures 3 and 6, the groove seats 56 fitting against the bars and angularly locking therewith.

The wear plates 13 and 14 are thus locked from outward movement at the tops by angularly overlapping with the transverse bars 51 and locked from outward movement at the bottom by angular overlapping with the shelf or lug projections 46.

The hollow body 42 of the main casting of the rocker is transversely perforated to receive the vertically movable horizontal bars 53 and is bored vertically to receive the vertical rods 55 and springs 54. The cover 43 of the rocker is removably bolted at 51 upon the top of the body portion 42.

The cover 43 extends along the top of the main rocker 12, affords support for the upper ends of the compressed springs 54 and also provides an upward extension from the rocker that effectively guides the raw material fed into the hopper 58 to opposite sides of the rocker member.

Special features of my invention are directed to the anvil members which are supported in a way that maintains them normally stationary during normal crushing yet permits them to yield resiliently if subjected to abnormal stresses incident to the entry of an uncrushable body between the anvil and the rocker member.

The anvils are counterparts, each presenting an anvil face 15 or 16 that is represented as part of a removable wear plate mounted upon a body 59.

The wear plate 15 or 16 and the body 59 carrying the wear plate both downwardly diverge in width to register with the corresponding diverging plate 13 or 14 upon the rocker 12.

The anvil plate 15 or 16 is removably mounted

upon the body 59 of the anvil and detail features of the invention are directed to the connection between the body and plate portions of the anvils.

The chamfered upper edge of the plate 15 or 16 makes an acute angle interlock at 60, Figure 8, with a downwardly directed abutment across the top of the body, the plate being pressed resiliently upwardly at the bottom and locked from outward movement at the bottom by the wedge heads 61 of the bolts 62.

The bolts 62 extend diagonally upwardly through perforations in the body 59 of the anvil and are surrounded back of the anvil by springs 63. The springs 63 are adjustably compressed between the back of the anvil and washers 64 by lock nuts 65 on the ends of the bolts and the resilient pull of the bolts maintains each anvil plate, 15 or 16 in tight locking connection at its top and bottom edges with the body of the anvil.

As illustrated each anvil plate is held to its position upon the anvil body by two bolts 62 as best seen in Figures 3, 5 and 8.

The body of the anvil is supported at the top from moving upwardly and rearwardly by an arcuate knee projection 66 which presents its curved arcuate surface against the correspondingly concaved surface of a downwardly and inwardly presented pillow bearing 67, which is part of the stationary frame structure.

The knee portion 66 of the anvil body is bored axially of the arcuate surface and slotted transversely at 68 and 69 from the outside of the knee inwardly to receive the eye portions of eye bolts 70.

Each body is provided with a bolt or pin 71 axial of the arcuate surface of its knee through the eyes of the bolts 70. The bolts 70 pass diagonally outward and upward through perforations 72 of the stationary pillow bearing 67 and are surrounded and pulled upward by springs 73 adjustably compressed between the upper sloping face of the pillow and washers and lock nuts at 74 on the upper ends of the bolts.

The function of the bolts 70 is merely to hold the anvils from moving downward away from their knee engagements with the pillow bearings 67.

The anvils are supported from moving rearwardly at the bottom by toggle mechanism between the back of each anvil near the bottom thereof and a stationary bearing supported by the frame structure. Each toggle is normally a little off dead center with the central or key members of the toggle strongly pressed resiliently toward their dead center positions, whereby a force applied to the front of either anvil sufficient to cause any bending of its toggle must overcome an adjustably heavy retraction of a spring tending to straighten the toggle.

Due to the normally nearly straight position of the toggle, a large component of the force on the lower end of the anvil will be rigidly carried by the toggle, and only a small component will be borne by the spring. Until the force on the spring is relatively great, the toggle will maintain its position, but as soon as the spring begins to yield, further yielding will be quick and easy, as the proportion of the total force which acts on the spring will increase as the toggle breaks.

Thus there will be a snap or trigger action, once an excessive pressure is applied to the anvil due to the presence of an uncrushable object between the crusher jaws. This snap yielding action is preferable to the ordinary resilient yielding of a spring acting directly against the

anvil, because it quickly withdraws the anvil from its normal position, thus frequently preventing breaking of the jaws which would otherwise occur. As the pressure on the front of the anvil builds up beyond normal crushing pressure, the resistance on the back of the anvil rapidly decreases, saving the jaws from breakage.

The preferred form of toggle comprises an intermediate head or key 75 and toggle arms 76 and 77 along opposite sides of the head or key 75, and respectively engaging the back of the anvil and the stationary bearing.

The head or key 75 is suitably a cylindrical body provided with flat seats 78 at intervals along its upper side and vertically bored at the middle of each seat to loosely pass the lower ends of bolts 79.

The bolt members 79 are adjustably fastened at their upper ends at 80 to a horizontal rocker shaft 81 pivotally mounted in the stationary frame structure at 82. They pass down through suitable openings 83 in the top of the frame structure and below these openings carry flanges 84 that are suitably welded to the bolts and provide abutments to receive the upper ends of springs 85.

The springs 85 surround the bolts and are compressed between the seat portions 78 of the head or key member 75 and the flanges 84, and, since the upper ends of the bolts are anchored, the springs 85 tend to downwardly press (straighten out) the toggle. Collars 86 fastened to the bolts at their lower ends limit the downward movement of the head or key member 75 along the bolts.

The vertical perforations through the head or key member 75 permit easy sliding of the head or key member along the bolts, provided the compressive force of the springs 85 is overcome.

The vertical adjustment at 80 in the position of the bolts limits the normal approach of the toggle joint to its dead center position by determining the vertical position of the stop collars 86 on the lower ends of the bolts.

The toggle arms 75 and 76 are suitably alike, of rail section, each presenting a concaved base flange 87 to one side of the cylindrical head or key 75 along substantially the entire length thereof, and each presenting a rounded head 88 to the back of the anvil in a suitable concave seat 89 or to the stationary support at a concave bearing 90. The toggle arms have webs 91 between their head and base portions.

At the ends of the toggle arms 75 and 76 ribs 91' extend across the ends of the head or key 75, and pivot pins 91" pass through the ribs 91' into the ends of the head or key 75.

When the toggle bends and straightens, the toggle arms pivot at one side about the horizontal axes of the heads 88 and pivot at the other side about the horizontal axis of the cylindrical head or key 75, the head or key sliding vertically on the lower ends of the bolts 79.

The concave stationary bearing 90 supports the bottom of the anvil from yielding rearwardly during normal stone crushing and comprises an angle member having a flat base seated along a horizontal step 92 and a vertical back adjustably spaced from a riser portion 93 of the step by suitable shims 94 between the bearing and riser. The step structure is a portion of the stationary frame of the machine.

While I prefer to make the bearing surfaces of the toggle include convex surfaces along opposite sides of the key and concave surfaces along the

back of the anvil and along the stationary bearing 90, with mating surfaces respectively concave and convex, the form of the toggle may be changed somewhat according to preference and somewhat according to special conditions. For example, either one of any pair of interfitting mating surfaces may be convex with the other surface concave.

As illustrated, the key or head 75 of each toggle is provided with three suspension bolts 79, 10 see Figure 5, the bolts being free to rock by angular movement of the suspending rocker shaft 81.

It will be understood that the force on this shaft is relatively small, the bolts normally pressing upwardly somewhat upon the shaft 81 and pressing more upwardly the more the toggle joint is deflected out of its normal position. The upward pressure is that due to the compression of the springs 85 upon the flanges 84 of the respective bolts.

The top of the crusher is provided with a removable hopper 58 for receiving the raw material and guiding this material to the crushing jaws. The hopper 58 should be readily removable and may be adapted to merely lift away, with suitable fit at the bottom to prevent displacement during normal use.

In normal operation the stones placed in the hopper deliver alternately to opposite sides of 30 the main rocker, to one side of the rocker during retraction of that side from its cooperating stationary anvil and the crushing of stones at the other side and then to the other side of the rocker on the next stroke with crushing of stones 35 at the first side.

The anvil members are substantially stationary throughout normal crushing, the position during crushing being that indicated by the anvil on the right side of Figure 3. Abnormally heavy 40 force is needed to open the toggle support at the back of the anvil.

In the event of an uncrushable body such as a piece of iron entering the crusher at one side, the anvil is deflected outwardly at the bottom 45 as indicated on the left side of Figure 3. The deflecting movement is initially heavily resisted by the spring 85, the resisting force progressively diminishing however with great rapidity as the toggle progressively bends.

It will be understood that while the upper ends of the springs 85 should preferably engage flanges 84 integral with the bolts 79, the springs may be supported for compression in any suitable way, as by engaging downwardly directed abutments of the stationary frame structure. The latter method of support is less desirable, chiefly by reason of less easy angular accommodation of the bolts and spring members during bending of the toggle.

The principal functions of the bolts 79 are to provide efficient mounts for the springs 85 and means for easily adjusting the extent to which the toggles are straightened out in their normal undeflected positions. The degree of straightening of the toggles is determined by the vertical position of the stop collars 86 beneath the head or key members 75 of the toggles. Obviously the downward straightening movement of the toggle may be adjustably limited in any suitable way other than that shown.

In the event that one or more of the wear plates 13, 14, 15 and 16 need replacement, whether on the rocker or on one of the anvils, the hopper 58

may be lifted away and one or both of the filler members 49 and 50 at the ends of the rocker, which also overlap the ends of the anvils, are then preferably removed. The nuts upon the 5 bolts 52 are accessible from the outside and the bolts are kept from turning by their square heads fitting in square recesses on the interiors of the filler members.

When the filler members have been lifted out 10 any one of the wear plates may be removed without need for removing either the anvil or the rocker, although both anvil and rocker are also readily removable.

I find resilient connection of the wear plates 15 to the crusher jaws to be very desirable, as it permits slight movement of the wear plates in case some uncrushable object is caught between the jaws, thus relieving excessive stresses and preventing breakage.

20 To remove the anvil, the nuts on the upper ends of the suspension bolts 10 are loosened and the pins 11 through the axes of the knees 66 are pulled out (being accessible through suitable openings 95 in the end walls 47 and 48 of the frame and shell structure). The anvil may be 25 then lifted away.

If desired, an anvil plate 15 for example, may be removed and replaced by a new plate without 30 taking out the anvil. This may be done by simply loosening the nuts 65 that wedge this plate up resiliently to lock it at top and bottom.

As soon as the bolts 62 have been moved somewhat diagonally downwardly, the wear plate is free to slide out at the top and then to be lifted 35 away.

The resilient connection between the link 21 and the lower end of the main rocker is readily disconnected as by loosening the plate 41 from the top of the opening around the link, loosening 40 the nuts 32 at the upper ends of the tie bolts 26 and 27, then removing the screw pins at 28 that pivotally connect the tie bolts to the outer end of the link.

When these pins have been removed the whole 45 rocker may be lifted out after removal of the cap portions of the horizontally divided pillow block bearings at 11.

In the same way the link and drive shaft may be moved out horizontally after taking off the 50 cap portions of the vertically divided pillow block bearings 25 of the drive shaft.

The faces of the wear plates are suitably provided with sloping serration flutings as best seen in Figures 2, 5 and 6. These flutings effect a 55 more uniform distribution of the crushing material across the widths of the cooperating jaws as the material delivers downward between the crushing members.

The flutings 96 on one side of a vertical center 60 plane through the plate are preferably parallel to one another and to that side of the plate and the flutings 97 on the other side of the middle line of the plate are in the same way parallel to one another and to the other side of the plate, the said flutings 96 and 97 relatively diverging 65 downwardly, as clearly shown in the figures.

It will be evident that the principles of my invention may be applied in other settings, where 70 for example both crusher jaws move, instead of one remaining normally stationary, and that the snap release in case of overload of the jaws could be applied to either jaw or to both jaws.

The use of a head and socket connection between the rocker and the link greatly simplifies 75 the construction and avoids expensive bearings.

It will also be evident that the principles of my invention may be applied to other crushers besides stone crushers, although stone crushers are the preferable embodiment.

In view of my invention and disclosure variations and modifications to meet individual whim or particular need will doubtless become evident to others skilled in the art, to obtain all or part of the benefits of my invention without copying the structure shown, and I, therefore, claim all 10 such in so far as they fall within the reasonable spirit and scope of my invention.

Having thus described my invention, what I 15 claim as new and desire to secure by Letters Patent is:

1. In a crusher having a rocker and a jaw face thereon, an anvil and a support holding the anvil in cooperating relation with the jaw face, said support including stationary framework, a socket joint between the framework and anvil at the 20 top and rear of the anvil, preventing bodily upward and rearward yielding of the anvil at the said joint and permitting angular movement of the anvil about the joint, means for holding the anvil in the socket, a stationary abutment rearwardly spaced from the anvil at the lower end thereof, a toggle between the abutment and the anvil, the toggle blocking the lower end of the anvil from moving toward the abutment and having a position during normal crushing near to 30 but away from the dead center position of the toggle, means including springs for retaining the toggle in its normal position adapted to release under abnormally high pressure upon the anvil, said means for retaining the toggle in its normal position including a stop engaging directly 35 against the toggle for preventing the toggle from moving into its dead center position.

2. In a crusher having a rocker and a jaw face thereon, an anvil and a support holding the anvil in cooperating relation with the jaw face, said support including stationary framework, a diagonally downwardly open knee and socket joint between the framework and anvil at the top and rear of the anvil, preventing bodily upward and rearward yielding of the anvil at the 40 said joint and permitting angular movement of the anvil about the joint, means for holding the anvil in the socket, a stationary abutment rearwardly spaced from the anvil at the lower end thereof, a toggle between the abutment and the anvil, the toggle blocking the lower end of the anvil from moving toward the abutment and having a position during normal crushing near to 45 but away from the dead center position of the toggle, means including springs for retaining the toggle in its normal position adapted to release under abnormally high pressure upon the anvil, said means for retaining the toggle in its normal position including a stop engaging directly 50 against the toggle for preventing the toggle from moving into its dead center position, and means for adjusting the stationary abutment with respect to the anvil in order to adjust the normal position of the anvil with respect to the rocker. 55

3. In a crusher having a rocker and a jaw face thereon, an anvil and a support holding the anvil in cooperating relation with the jaw face, said support including stationary framework, a socket joint between the framework and anvil 60 at the top and rear of the anvil, preventing bodily upward and rearward yielding of the anvil at the said joint and permitting angular movement of the anvil about the joint, a stationary abutment rearwardly spaced from the anvil at 65

- the lower end thereof, a toggle between the abutment and the anvil, the toggle including a toggle arm presenting one side against the anvil, a second toggle arm presenting one side against the abutment, a vertically movable head or key receiving on its opposite sides the other of the toggle arms, a spring seat secured to the head or key, a spring pressing against the spring seat and urging the head or key in a direction to straighten the toggle and a stop operating against the head or key and limiting the normal position of the toggle to one near to but away from that of straight alignment of the toggle arms.
4. In a stone crusher having a rocker and a jaw face thereon, an anvil cooperating with said face, a pillow bearing supporting the upper end of the anvil from moving upwardly and rearwardly, an abutment rearwardly spaced from the anvil near the lower end thereof, a toggle connection between the abutment and the lower end of the anvil, the said toggle connection including a rocker shoe presenting one side against the anvil, a second rocker shoe presenting one side against the abutment, a vertically movable head or key receiving on its opposite sides the other sides of the rocker shoes, a bolt passing through the head or key in a direction generally transverse to the straightened toggle, means for supporting the bolt against vertical movement, a collar on the bolt below the head or key limiting the straightening of the toggle, a carrying flange above the toggle and a spring around the bolt compressed between the flange and the head or key.
5. The structure of claim 4 in which the means for supporting the bolt against vertical movement is longitudinally adjustably connected to the bolt.
6. The structure of claim 4 in which the means for supporting the bolt against vertical movement includes a horizontal rocker for angular accommodation of the bolt to the toggle.
7. In a crusher, an anvil, a rocker pivoted near its top, having a lateral jaw face lower than the pivot in cooperative relation with the anvil, the said rocker extending downwardly beyond the jaw face for connection to a link, a link, a head and socket connection between the link and the rocker, spring means holding the bearing surfaces of the head and socket connection in close engagement and means for reciprocating the link.
8. In a crusher, an anvil, a rocker pivoted near its top, having a lateral jaw face lower than the pivot in cooperative relation with the anvil, the said rocker extending downward beyond the jaw face for connection to a link, a head on the lower end of the rocker, a link having a socket receiving the head on the bottom of the rocker, spring means holding the head in the socket and means for reciprocating the link.
9. In a crusher, an anvil, a rocker pivoted near its top, having a lateral jaw face lower than the pivot in cooperative relation with the anvil, the said rocker extending downwardly beyond the jaw face for connection to a link, a head on the lower end of the rocker, a link having a downwardly tapering socket, shoes fitting the tapered walls of the socket and presenting inner curved surfaces which engage the opposite sides of the head on the lower end of the rocker, a spring wedging the shoes down about the head and means for moving the link.
10. In a crusher, an anvil, a rocker pivoted near its top, having a lateral jaw face lower than the pivot in cooperative relation with the anvil, and
- the said rocker extending downwardly beyond the jaw face for connection to a link, a link, a head and socket connection between the link and the rocker, a flexible seal covering the head and socket connection and means for reciprocating the link.
11. In a stone crusher having a rocker and a jaw face thereon, a normally stationary anvil cooperating with the jaw face, a rearwardly and upwardly presented knee on the anvil, a stationary concave pillow bearing for the knee, spaced tie bolts pivotally connected to the knee and extending rearwardly and upwardly, a rearwardly and upwardly directed stationary abutment along an intermediate portion of each tie bolt, a spring surrounding each tie bolt above the abutment, a nut on each tie bolt beyond the spring compressing the spring against the abutment thereby causing the tie bolts to resiliently hold the knee against its pillow bearing, and means for preventing rearward movement of the anvil at the lower end thereof during normal crushing between the jaw face and anvil and for permitting the said rearward movement responsive to pressures upon the crushing face of the anvil greater than those incident to normal crushing.
12. In a double acting crusher, a main rocker having horizontal pivot support and downwardly diverging sides below the pivot, wear plates removably mounted on the sides, engaging and being held to the rocker at the bottom by projections from the rocker sides under and angularly locking with the bottoms of the wear plates, spaced horizontal cross bars whose opposite ends are supported upon and angularly lock with the tops of the respective plates, a cap secured upon the top of the main rocker, vertical pressure bars pressing against the horizontal cross bars, and spring means acting between the cap and vertical pressure bars in recesses of the main rocker and urging the vertical pressure bars and through them the horizontal cross bars downwardly toward their holding positions.
13. In a crusher, a generally vertical rocker pivoted near the top and having a crusher jaw on one side, means for reciprocating the rocker, a generally vertical anvil cooperating with the crusher jaw on the rocker and having a knee near its upper end, a socket engaging the knee and pivoting the anvil, spring means urging the knee into the socket, a toggle holding the lower end of the anvil and a spring urging the toggle against breaking.
14. In a crusher, cooperating crusher jaws, means for relatively reciprocating the jaws, a toggle supporting one end of one of the jaws, spring means urging the toggle against breaking and a support for the spring pivoted near one end, extending to the toggle and positioning the spring between the pivot and the toggle, whereby, with movement of the toggle, the lateral movement of the spring will be a maximum adjacent the toggle and will decrease toward the pivot.
15. In a crusher, cooperating crusher jaws, means for relatively reciprocating the jaws, a pivot for the upper end of one of the jaws, a toggle supporting the lower end of said jaw, a spring urging the toggle against breaking and a support for the spring pivoted near one end, extending to the toggle and positioning the spring between the toggle and the pivot of the support for the spring.
16. In a crusher, a generally vertical rocker pivoted near its upper end, means for reciprocating the rocker, a generally vertical anvil cooperat-

5   ing with the rocker having a knee near its upper end, a socket engaging the knee, a toggle supporting the lower end of the anvil comprising a pair of toggle arms and a toggle head between the arms, a bolt pivoted at one end and extending to the toggle head, a spring surrounding the bolt between the pivot point of the bolt and the head and an abutment engaging one end of the spring, whereby the spring will swing with the bolt about the pivot of the bolt when the toggle breaks.

10   17. In a crusher, a rocker, an anvil pivoted at its upper end, a toggle supporting the lower end of the anvil and comprising toggle arms and a toggle head between the toggle arms, a spring urging the toggle against breaking and a support for the spring pivoted beyond the end of the spring remote from the toggle.

15   18. In a crusher, a rocker hanging vertically, pivoted near the top and having a crusher jaw on one side, means for reciprocating the rocker, a generally vertical anvil cooperating with the crusher jaw on the rocker and having a knee near its upper end, a frame member having a socket engaging the knee and pivoting the anvil, a spring means urging the knee into the socket, a toggle supporting the lower end of the anvil, a continuously compressed spring urging the toggle against breaking and acting between said frame member and one side of the toggle and means acting between said frame member and the other side of the toggle and positively holding the toggle away from its dead center position.

EDWARD T. PETERSON.
